LLP(57) **CLAIM**

The ornamental design for a housing for surveillance camera, as shown and described.

DESCRIPTION

FIG. 1 is a front elevation view of a housing for a surveillance camera showing my new design;

FIG. 2 is a side elevation view thereof;

FIG. 3 is a rear elevation view thereof;

FIG. 4 is an opposite side elevation view thereof;

FIG. 5 is a bottom plan view thereof; and,

FIG. 6 is a top plan view thereof.

The broken lines depict portions of a housing for surveillance camera in which the design is embodied and form no part of the claimed design.
